HANDLE FOR A CASSEROLE OR THE LIKE

Manuel S. Ziskin, Mayfield Heights, and Harold O. Wagner, Sheffield Lake, Ohio, assignors to American Trading & Production Corporation, Baltimore, Md.

Filed July 11, 1974, Ser. No. 487,599

Term of patent 14 years

Int. Cl. D8—06

U.S. Cl. D7—132

Fig. 1

Fig. 2

Fig. 3

FIG. 1 is a top plan view of a handle for a casserole or the like showing our new design;

FIG. 2 is a side elevational view; and

FIG. 3 is a bottom plan view thereof.

We claim:

The ornamental design for a handle for a casserole or the like, substantially as shown.
